UNITED STATES PATENT OFFICE.

EMMOR J. STEWART, OF NEW YORK, N. Y.

SCRUBBING-MACHINE.

No. 824,958.

Specification of Letters Patent.

Patented July 3, 1906.

Application filed June 8, 1904. Serial No. 211,623.

To all whom it may concern:

Be it known that I, EMMOR J. STEWART, a citizen of the United States, residing at New York city, borough of Manhattan, and State 5 of New York, have invented certain new and useful Improvements in Scrubbing - Machines; and I do hereby declare the following to be a full, clear, and exact description of the invention, such as will enable others 10 skilled in the art to which it appertains to make and use the same, reference being had to the accompanying drawings, and to figures of reference marked thereon, which form a part of this specification.

15 My invention relates to scrubbing-machines; and it has for its object to provide means for propelling the machine by mechanical power and like means to simultaneously rotate a scrubbing-brush and operate a mop 20 and wringing device, means whereby the entire structure may be thrown into and out of operation at will; and it further consists of such details of construction and the operation of parts as will be hereinafter described and 25 claimed.

Referring to the drawings, in which like parts are similarly designated, Figure 1 is a side elevation, parts being broken away, of the entire machine. Fig. 2 is an elevation of 30 the opposite side. Fig. 3 is a front view. Fig. 4 is a plan-view of the reversible guide-frame for the mop. Fig. 5 is an end view of the same. Fig. 6 is a vertical section taken just behind the motor-shaft and looking forward. Fig. 7 is an enlarged detail side view of the means for adjusting the rollers of the reversible frame. Fig. 8 is a plan of Fig. 7. Fig. 9 is an enlarged detail elevation of one side of the mop-frame mounted in the 35 tank, the latter being shown in vertical section. Fig. 10 is an enlarged detail plan view of the clutch and its operating-lever. Fig. 11 is a detail view of a spring for holding the clutch-operating lever in position.

40 The numeral 1 designates a rectangular frame, preferably made of metal, having depending arms 2, one on each side. In the lower ends of said arms is mounted an axle 3, to which are secured two traction-wheels 4, 5, 45 and on the end of said axle next to wheel 4 is secured a sprocket-wheel 6. These wheels 4 and 5 support the forward end of the frame 1, and the rear end is supported by a caster-wheel 8, mounted in a forked standard 8^a, 50 swiveled in a socket 7, depending from a

cross-piece 1^a of the frame 1. A brace 7^a is provided to steady the socket.

Across the frame 1 is mounted a shelf 9, which supports an electric motor 10, the armature-shaft 11 of which is prolonged on each side of the motor and passes through and is supported by brackets 12 and 13. On said armature-shaft 11 is pivoted two arms 14, connected by crossed braces 15 and 16, the ends of the arms 14 being provided with 60 bosses 17, that form supports for a frame carrying splash-boards or fenders 18 and journals for the ends of an axle 19 of a rotary scrubbing-brush 20. The axle 19 of the brush is extended through one of the bosses 65 17 to receive a sprocket-wheel 20^a, which is connected by a drive-chain 21 with a sprocket-wheel 22 on the armature-shaft 11.

On the end of the armature-shaft opposite the wheel 22 is fixed a gear-wheel 23, carrying a clutch member 24, Fig. 10, and loose on this shaft is a shifting spool 26, carrying complementary clutch member 25, a sprocket-wheel 27, and a gear-wheel 28. The traction-wheels 4 and 5 are propelled through 80 the medium of a chain 29, connecting the sprocket-wheel 6 on the traction-wheel shaft with the sprocket-wheel 27 on the armature-shaft. The gear-wheel 23 meshes with a transfer-pinion 32, mounted on a stub-shaft 85 32^a, journaled in a bearing 32^b, mounted on the top of one of the side pieces of the rectangular frame. This pinion 23, through the medium of transfer-pinion 32, drives a pinion 33 on a shaft 34, journaled in two sides plates 43, 90 secured to the side pieces 1, and said shaft also carries a gear-wheel 35, and when the clutch members are engaged, as shown in Fig. 3, wheels 28 and 35 are out of gear and motion is communicated through chain 29 95 directly from the motor-shaft to the traction-wheel shaft and the machine is driven in the same direction as the motor-shaft. On throwing the clutch out of gear wheel 28 when thrown far enough over will engage 100 wheel 35 and with the sprocket-wheel 27 be indirectly driven from the armature-shaft 11 in a reverse direction through gears 23, 32, 33, and 35.

For shifting the clutch member 25 I provide a hand-operated angle-lever 30, Fig. 10, fulcrumed on a bracket 30^a, secured to one of the arms 14. A spring 30^b, mounted on top of the arm, forms between its center and two ends two pockets or recesses 30^c and 30^d, 110

Fig. 11. When the clutch is thrown out of gear, the short arm of said lever 30 will be held in pocket 30^d, as shown in Fig. 10, and in pocket 30^e when the clutch is thrown into gear.

On the shaft 34 is mounted the upper squeezing or wringer roller 36, which is either made of rubber or provided with a rubber surface. This shaft 34 also carries a gear-wheel 37, that meshes with a gear-wheel 38 on a shaft 39, which latter carries another rubber or rubber-surfaced wringer or squeezing roller 40. The shaft 39 projects through the plates 43 and is journaled in bearing-pieces 41, supported on the frame and adapted to be raised and lowered, by means of screws 42, to move the lower roller to and from the fixed roller, so that mops of different thickness may be used. Pockets 44 are preferably formed on the plates 43, into which the ends of bearing-pieces 41 project for the purpose of protection.

A receiving-tank 45, preferably constructed with curved ends and provided with a draw-off aperture having a screw-plug 46 in its bottom, is secured to the plates 43.

On each side of the frame 1 are two depending hooks 47 to receive a bail 48 of a receiving-pail 49 or other receptacle. A pipe 50, preferably a flexible one, connects each pail with the receiving-tank near its top, whereby the water may be drained from the tank into the pails; and sufficient space is provided between the pails for the free movement of the caster-wheel 8.

My mop-guide frame is reversible and portable and may be easily and readily removed from the receiving-tank 45 for the purpose of cleaning it and the tank, as will be hereinafter explained. It consists of two plates 51, having ends curved alike, Figs. 4 to 8; joined centrally by a bar 52, rectangular in section and having rounded ends. These plates are connected to the bar by angle-plates 53, thus forming a rigid frame. Journaled in and extending between the plates 51 are two cleaning-brushes 54. On the axle of each brush on the outside of one plate is a gear 55 and a sprocket-wheel 56. As shown in Figs. 7 and 8, a slot 57 is formed in each end of the plates 51, through which the ends of shafts 59^a of roller 59 project. These shafts also project through the ends of a yoke 58, which straddles each end of the plates 51, and each yoke 55 carries an adjusting-screw 58^a, which works in screw-threads formed in the ends of the plates. By this means it will be seen that the shafts may be shifted in the slots 57, moving the rollers 59 to and from the brushes 54, as desired.

A guard-plate 60, Figs. 4, 5, and 9, of sheet metal, extends between the plates 51, and on said plates 51 are lugs 62, in which are swiveled adjusting-screws 63. These screws 65 pass through the guard-plate at the sides and

carry nuts 64, that bear on said guard-plate, whereby when the nuts are screwed up in the direction of the lugs the ends of the guard-plate are pressed out and brought in the desired proximity to the brushes 54 for the purpose of bringing the mop into contact with the lowermost brush, as clearly shown in Fig. 9.

The round ends of the bar 52 are seated in vertical slots 65, formed in the sides of the tank 45, said slots terminating just above the lower edges of the plates 43, which serve to hold the bar 52 against lateral movement in the slots. The length of the bars 51 is so proportioned in regard to the depth of the tank that the lowermost roller 59 is held near the bottom thereof and the uppermost gear 55 of one of the brushes meshes with gear 37 on the squeezing-roller 36, which latter receives motion through the medium of gearing 85 driven by the armature-shaft, as above described.

When the machine is in operation, the lowermost brush 54 is rotated by the uppermost brush through the medium of sprocket-wheels 56 and drive-chain 61, the lowermost brush only acting on an endless mop 66. This mop passes from the floor on which it is dragged first through one of a pair of guides or shields 67, detachably hung from a rod 67^a, extending between the plates 43, then over one of a pair of guide-rollers 68, having bearing in notches 69 in the plates 43. On the axle of each guide-roller 68 is mounted a sprocket-wheel 70, connected by a drive-chain 71, that is driven by a sprocket-wheel 73^a on the axle of the lower squeezing-roller 40, which, as before described, is driven by the upper roller 36. From the roller 68 the mop descends into the tank 45 and passes under the lowermost idle roller 59, journaled in the plates 51, thence upward between the lowermost brush 54 and the spring guard-plate 60. The mop then passes between the wringer-rolls 36 and 40 and under, but not in contact with, the upper rotating brush 54 and over the other end of the guard-plate to the second roller 68, descending through the other detachable guide 67 to the floor. When the direction of travel of the machine is reversed and it becomes desirable to reverse the mop-frame, the rounded ends of the bar 52 will freely rotate in the slots 65. The uppermost roller 59, Fig. 9, is brought to the bottom of the tank and becomes the guide-roller for the mop, and its brush will engage the mop, while the lowermost roller and brush, Fig. 9, will be swung up, and the gear on the latter will engage the gear on the upper wringer-roller on the left. Spring-bolts 72 are mounted on yokes 58 and engage sockets formed on the upper edge of the frame 1 and lock the mop-frame to the tank. Braces 73 74 rise from the frame 1 and support a shelf 75, on which is mounted a pail 76, pro-

130

vided with a spigot 77, connected by a pipe 78 to sprinkler-pipes 79 and 80, mounted, respectively, in front of and behind the rotary scrubbing-brush 20. Each sprinkler is preferably provided with a hand-valve 81 82, respectively, by means of which water from the pail 76 may be distributed in front of or behind the brush either simultaneously or independently. On the shelf is also mounted a suitable double-pole switch 83 for reversing the direction of rotation of the shaft 11 and a resistance-box or controller 84. Back of the motor 10, supported by the frame 1, is a storage battery 86^a, connected, through switch 83 and controller 84, to the motor 10. Between the extensions of braces 73 is secured a rod 85, serving as a handle to guide the machine, and a rod 86 is pivoted on the armature-shaft and carries a spring-urged pawl 87, that engages a toothed sector 88, fixed on the brush-frame 14, so that this frame, with the brush, may be raised and lowered, being revolved about the armature-axle as a center. The pawl 87 is connected by a wire 89 to a finger-grip 90, pivoted at 91 on the handle portion 92 of rod 86. An arc 93 is mounted on the braces 73 and 74 and has on one of its inner faces a toothed rack 94, Fig. 3, that engages teeth 95 on one side of the lever 86. The opposite side of the lever is provided with a leaf-spring 96, that bears on the opposite smooth face of the arc and holds the lever in contact with the rack in any position. By pressing the lever against the spring the teeth and rack are disengaged, and the lever may be freely raised and lowered.

Having thus described my invention, what I claim as new therein, and desire to secure by Letters Patent, is—

1. In a scrubbing-machine, the combination with a tank and an endless mop adapted to be dragged on the floor, of means to guide the mop through the tank below the surface of water therein, means to brush the mop and means to wring the same after being brushed.

2. In a scrubbing-machine, the combination of a tank, an endless mop, a reversible frame for the mop mounted in said tank, a guide-roller for the mop at each end of the frame and a brush mounted contiguous to each roller adapted to alternately engage said mop.

3. In a scrubbing-machine, the combination with a tank and an endless mop surrounding the same, of feed-rollers for the mop, a guide-frame between the feed-rollers to guide the mop into the tank, a brush below the surface of water in the tank, a brush above said surface, a wringer between the brushes and means for holding the mop against one of said brushes.

4. In a scrubbing-machine, the combination with the main frame, a tank mounted thereon, a wringer mounted above the tank

and means for operating the wringer, of an endless mop in the wringer, a frame in the tank to guide the mop, a brush in the guide-frame engaging the mop before reaching the wringer, and means in the guide-frame for holding the mop in engagement with the engaging brush.

5. In a scrubbing-machine, the combination with the main frame, a tank mounted thereon, an endless mop surrounding said tank, feed-rollers mounted on the latter, of a guide-frame, idle rollers mounted in each end thereof, a brush in the frame near each roller, means in the frame for holding the mop in contact with one of the brushes, and means for driving the feed-roller and brushes.

6. In a scrubbing-machine, the combination with a tank, an endless mop, and rollers for feeding the mop, of a reversible frame, comprising two side plates, a shaft connecting the same, an idle roller in each end of the plates, brushes mounted between the rollers, and a guard-plate mounted in the frame between the brushes.

7. In a scrubbing-machine, the combination with a tank, an endless mop and rollers for feeding the latter into the tank, of a guide-frame comprising two side plates, a central connecting-shaft, an idle roller mounted between the plates at each end, a brush mounted in the plates next to each roller, means for adjusting said rollers relatively to the brushes, a guard-plate mounted between the brushes, and means for adjusting the end of the guard-plate to and from the brushes.

8. In a scrubbing-machine, the combination with the main frame and a tank mounted thereon, of wringer-rolls journaled above the tank, means to rotate said rolls, a feed-roller on each end of the tank, a drive-chain connecting one of the wringer-rolls with said feed-rolls, a guide-frame for the mop, brushes in said frame adjacent to said mop, and means for driving said brushes from the wringer-rolls.

9. In a scrubbing-machine, the combination with a motor, of a wringer, and an endless mop driven by said motor and means to reverse the direction of motion of said mop and wringer.

10. In a scrubbing-machine, the combination with a motor, of a wringer, an endless mop and traction-wheels, all driven by said motor, and means to reverse the direction of travel of the traction-wheels without reversing the direction of travel of the mop and wringer.

11. In a scrubbing-machine, the combination with a wheeled supporting-frame, a motor to propel the same, a tank carried thereby, an endless mop adapted to be dragged on the floor, means operated by the motor to wring the mop in the tank and means operated by the wringer to brush the mop before being wrung.

12. In a scrubbing-machine, the combination with a motor, of a wringer geared thereto, a mop, mop-feeding rollers, and a mop-cleaning brush geared to the wringer.
13. In a scrubbing-machine, the combination with a motor, of a wringer geared thereto, a mop, mop-feeding rollers, a chain connecting one of the wringer-rollers and the mop-feeding rollers, a brush geared to a wringer-roller, and a second brush driven by the first brush.
14. In a scrubbing-machine, the combination with a supporting-frame, wheels supporting the same, a motor mounted thereon, and a tank carried by the frame, of a wringer and a scrubbing-brush driven by the motor, a reversible frame in the tank, a guide-roller and a cleaning-brush at each end of the frame, a sprocket-wheel on each cleaning-brush, a chain connecting the sprocket-wheels, a gear-wheel on one of the wringer-rollers, an endless mop passing through the wringer and between the brushes, and a gear-wheel on each cleaning-brush adapted to be engaged by the gear on the wringer-roller. 25
15. In a scrubbing-machine, the combination with an endless mop and a tank through which the mop passes, of a wringer above the tank, a reversible frame, guide-rollers and mop-cleaning brushes mounted in the frame, 30 and a guide adjustable to and from the brushes.

In testimony that I claim the foregoing as my invention I have signed my name in presence of two subscribing witnesses.

EMMOR J. STEWART.
